LIST FINDER

Hildaur L. Neilsen, Metuchen, N. J., assignor to
The Bates Manufacturing Company, West
Orange, N. J., a corporation of New Jersey

Application March 24, 1945, Serial No. 584,577

11 Claims. (Cl. 40—104)

1

The present invention relates to an improved list finder and more particularly to a push-button controlled list finding device which is unusual in its simplicity and effectiveness of operation.

Devices of the present character, as heretofore constructed, have been provided with a slidable selector by means of which the desired list could be exposed to view. While these have been reasonably satisfactory they have certain recognized defects and disadvantages. Where the devices were intended for use in exposing alphabetically arranged telephone lists, for example, they could not conveniently be operated with one hand and after considerable use were apt to stick or jam due to wear with consequent misalignment of the parts. Often separate sliding and depressing movements were required for operation. In some cases the devices were unnecessarily complicated and expensive to manufacture.

One of the objects of the present invention is to provide a push-button operated list finder which can be actuated by simple finger pressure to expose to view the desired list or information.

Another object of the invention is to provide a list finder having an unusually simple construction which has a long effective life and which is not subject to sticking or jamming due to misalignment caused by wear.

More specifically, an object of the invention is to provide a list finder in which a selected list can be exposed to view in a rapid, accurate manner by a single application of pressure in a single direction.

Other objects of the invention reside in the various structural combinations and details hereinafter described and claimed.

In the accompanying drawings in which a preferred embodiment of the invention has been shown:

Fig. 1 is a perspective view of my new list finder in a closed condition;

Fig. 2 is a longitudinal sectional view of the list finder of Fig. 1 taken along line 2—2 thereof;

Fig. 3 is a view similar to Fig. 2 but in which the list finder is in partially open condition;

Fig. 4 is a horizontal sectional view taken along line 4—4 of Fig. 2;

Fig. 5 is a transverse sectional view through the list finder taken along line 5—5 of Fig. 2 and

Fig. 6 is a disassembled detail view on an enlarged scale of a fragment of the inner end of one of the index cards of the list finder illustrating the manner in which the cards are mounted.

Like numerals designate corresponding parts

2

throughout the various views of the drawings.

My new list finder comprises a cover member 10, a base member 11 hingedly connected to the cover member and a set of index cards or the like 12—in this instance thirteen such cards are provided in a stack or pack. As will be hereinafter more fully explained the number of index cards is equal to the number of push-buttons provided in the cover member 10.

10 Cover member 10 is a metallic stamping of generally rectangular shape with a depending marginal flange 13, one portion 14 of which is bevelled and provided with a row of apertures in which the release- or push-buttons 15 are disposed. As will be observed from Fig. 1 alphabetical indicia are placed on the upper surface of the cover member 10 adjacent the release buttons 15, it being understood that the indicia may be of any desired nature, number and disposition 15 depending upon the particular list finder and the nature of the information to be exposed to view upon operation of one of the release buttons. The release buttons fit snugly within the apertures provided for them and each such button has an annular flanged base 16 which has a diameter greater than the release button aperture, thus preventing excessive outward movement of the release button and maintaining it normally in desired angular position under spring urging for actuation at will by the user.

Within cover member 10 a spring steel piece is disposed which can be either unitary with the cover member or, as shown, spot welded, brazed or otherwise suitably secured in place. This spring steel piece is made up of a U-shaped body portion 17, the forward part of which is formed into a plurality of spring fingers 18 equal in number to release buttons 15. Beyond the spring fingers is a pair of downturned apertured hangers 19. 20 and beyond the hangers is a pair of supporting extensions 20 having inwardly projecting lips 21. A wire bail 22 extends transversely of cover member 10 beneath spring fingers 18, turning rearwardly at right angles to pass over lips 21 and then through hangers 19 from which it extends downwardly and somewhat forwardly to a point near the base member 11 and finally horizontally outwardly through a bayonet slot 23 in each of the upstanding sides 24 of the base member.

As will be understood from Fig. 2 in particular, spring fingers 18 slope slightly downwardly to points below and in contact with release buttons 15 after which they curve backwardly, then downwardly and finally obliquely downwardly and rearwardly, terminating at the inner edge

of the rearwardly extending portion 25 of front cover flange 13. Bail 22 lies just below the fingers 18 in contact with or in close juxtaposition to the undersurfaces thereof. This bail 22 constitutes a releasing and locking means operating under the influence of the spring fingers in a manner to be hereinafter more fully explained.

Base member 11 has a pair of index card supports formed by striking up the base stamping to provide a pair of front and rear upturned members 26 on which cards 12 rest in flat but slightly inclined position as best shown in Fig. 2. The number of cards is equal to the number of spring fingers and release buttons and the forward edges of the cards are cut away as indicated at 27 to form tabs of successively decreasing widths from the top card to the bottom card of the stack in a manner per se known and shown in Fig. 4. The rearward portion of each card 12 is notched out at 28 on each side, providing a pair of tangs 29 insertible into the sockets 30, each of which has an apertured lug 31 configured as shown in detail in Fig. 6. Eyelets 32 pass through the cover and base flanges as illustrated in Fig. 4 and through the lugs 31 to 25 serve as stub shafts constituting a hinge connection. The eyelets are peened or turned down in the usual manner to form a permanent assembly. Washers or washer-like portion 33 are provided for the usual purpose. A coil spring 34, normally under tension, is anchored at one end to the cover flange 13, and at the other end to the base member 11. The exact manner of attaching the spring and the locations of the end anchors thereof is subject to variation but is preferably that shown; namely, an apertured central lug 35 in cover flange 13 and a short post 36 rising from base member 11.

Rubber or plastic or other non-scratching friction "feet" (not shown) are provided on the bottom of the list finder. Release buttons 15 are made of molded rubber or plastic or any other suitable material. The list finder may be finished in any desired or required manner and may be made of any one of a number of metals or alloys. It may have a metallic surface of bright or matte character or may be enamelled in any desired color. The list finder has the advantage of being very flat and free from external projections, except as to the push-buttons themselves.

Use and operation of the new list finder are exceedingly simple. Assuming that the list finder is closed as in Fig. 2, the user pushes on one of the buttons 15 with a finger to depress the same. Assume that the "CD" button is depressed. Pressure on such button 15 causes button base 16 to act on the underlying portion of spring finger 18 bending it into the shape shown in Fig. 3. This action depresses the transverse portion of bail or release bar 22, causing the end portions of the bail bar to slide rearwardly in slots 23 thus unlocking cover member 10. At the same time the terminus of the spring finger moves off the edge of flange 25 until that edge passes over the first "hump" and locks in the V-shaped depression therebeyond as clearly shown in Fig. 3 with the terminus or free end of the finger underlying the tab on the corresponding card. This movement of the spring finger and bail causes a corresponding movement of projecting lips 21 and supporting extensions 20, placing the latter under spring tension. Since the cover member has become unlocked it is free to rise to open position under the influence of coil spring

34 which is enabled to contract. As cover member 10 rises the terminus of the depressed spring finger picks up the corresponding index card tab directly thereabove and, of course, all alphabetically preceding cards so that the "CD" index lists are exposed to view. To close the list finder and re-set it for re-use, the user pushes the cover closed, whereupon the actions which occur are the reverse of those just described. Spring 34 gradually stretches and the bail bar ends follow along the sloping guide surface leading to slots 23 until the depressed spring finger terminus strikes against the bottom plate of the base member stamping 11, whereupon the spring finger is forced over the edge of flange 25 after which it snaps back to the position of Fig. 2 under the urging of members 20 and 21 and the inherent resilience of the spring steel of the spring finger itself. As this occurs release button 15 returns to the position of Fig. 2 and the bail bar ends again slide to the forward ends of slots 23, locking the list finder in closed position ready for use and a repetition of the described cycle of operations at the will of the user.

It is to be understood that the foregoing is presented as illustrative and not as limitative and that, within the purview of the appended claims, various additions, omissions, modifications and substitutions may be resorted to without departing from the scope or principles hereof. The number of index cards and release buttons, the alphabetical or other sequential nature of the lists and the arrangement thereof may be considerably varied depending upon the intended use of any particular list finder. That shown in the drawings is the type employed for finding telephone numbers in alphabetically arranged lists. It is further to be understood that the angular movement of the cover member of the list finder is greater than that indicated in Fig. 3 in order to provide ample visibility for the lists exposed to view. Limitations of space made it convenient to show only about a 45 degree movement of the cover member and angular movements up to approximately 90 degrees more or less are to be deemed to be a definite part of the invention. It is also to be observed that the index cards 12 are at no time subjected to any distortion or frictional sliding or bending movements and therefore are long lasting. They can, moreover, be replaced when necessary to change the lists in an extremely simple manner by slightly arching them transversely to slip the tangs 29 out of or into the sockets 30.

I claim:

1. A device of the character described comprising a base, a plurality of superimposed cards mounted on said base for swinging movement, a cover hingedly connected to said base, means normally urging said cover away from said base, means for releasably holding said cover in a position adjacent said base, and means for selectively connecting to said cover for movement therewith any number of said cards, said means including a finger piece movably mounted on said cover for each card and an element actuated thereby into a position to engage the corresponding card upon movement of said cover away from said base, and means common to all of said finger pieces for actuating said holding means to release said cover upon movement of any of said finger pieces.

2. A device of the character described comprising a base, a plurality of superimposed cards mounted on said base for swinging movement, a

cover hingedly connected to said base, a finger piece movably mounted on said cover for each of said cards, and an element actuated by each finger piece into a position to engage the corresponding card upon movement of said cover away from said base, and means normally actuating said element into a position to clear said cards upon movement of said cover toward said base.

3. The device as defined in claim 1, with the addition of means for releasably locking said elements in said card-engaging positions.

4. The device as defined in claim 1, wherein said elements are formed to releasably interlock with said cover in said card-engaging positions and said elements are released by engagement thereof with said base as the cover is moved toward said base.

5. The device as defined in claim 1 wherein each of said elements is a spring finger connected at one end to said cover and engageable intermediate its ends by the corresponding finger piece.

6. The device as defined in claim 1 wherein each of said elements is a spring finger connected at one end to said cover and engageable intermediate its ends by the corresponding finger piece and the other end portions of said fingers are formed to releasably interlock with said cover in said card-engaging positions.

7. The device as defined in claim 1 wherein each of said elements is a spring finger connected at one end to said cover and engageable intermediate its ends by the corresponding finger piece and the other end portions of said fingers are formed to releasably interlock with said cover in said card-engaging positions and are released by engagement of the ends of said fingers with said base as said cover moves toward the base.

8. The device as defined in claim 1 wherein each of said elements is a finger connected at one end to said cover and engageable by the corresponding finger piece, and said means releasably holding the cover adjacent said base includes a U-shaped bail having its arms pivotally connected to said cover and its main portion underlying all of said fingers to be actuated by any thereof.

9. The device as defined in claim 1 wherein each of said elements is a finger connected at one end to said cover and engageable by the corresponding finger piece, and said means releasably holding the cover adjacent said base includes a U-shaped bail having its arms pivotally connected to said cover and its main portion underlying all of said fingers to be actuated by any thereof, the extremities of said arms and said base having cooperatively engageable and disengageable portions to hold and release said cover respectively.

10. The device as defined in claim 1 wherein each of said elements is a finger connected at one end to said cover and engageable by the corresponding finger piece, and said means releasably holding the cover adjacent said base includes a U-shaped bail having its arms pivotally connected to said cover and its main portion underlying all of said fingers to be actuated by any thereof, the extremities of said arms and said base having cooperatively engageable and disengageable portions to hold and release said cover respectively.

11. A device as defined in claim 2 with the addition of means urging the cover into open position, and means for releasably holding the cover in closed position including a release bar having its central portion extending transversely of the cover beneath and in contact with all of said elements, whereby when any of said finger pieces is actuated said holding means is operated to release the cover.
